CLAIM

The ornamental design for a faucet control unit, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top, and right side perspective view of a faucet control unit;

FIG. 2 is a top plan view thereof in a first use position;

FIG. 3 is a top plan view thereof in a second use position;

FIG. 4 is a top plan view thereof in a third use position;

FIG. 5 is a bottom plan view thereof;

FIG. 6 is a front elevational view thereof;

FIG. 7 is a rear elevational view thereof;

FIG. 8 is a right side elevational view thereof; and,

FIG. 9 is a left side elevational view thereof.

The broken lines in the drawings illustrate environmental subject matter and form no part of the claimed design.
